4 Claims. (Cl. 299—13)

This invention relates to refrigerating apparatus and more particularly to an apparatus for cooling beverages, such as drinking water.

This application is a division of our copending application S. N. 309,216, filed September 29, 1928 and granted as Patent Number 2,051,874 for Refrigerating apparatus.

This application relates to water coolers, for instance of the type described in our Patent No. 1,847,092.

An object of this invention is to provide a sanitary top for a water cooling apparatus.

Further objects and advantages of the present invention will be apparent from the following description, reference being had to the accompanying drawings, wherein a preferred form of the present invention is clearly shown.

In the drawings:

Fig. 1 is a vertical cross-sectional view of a water cooling apparatus embodying features of this invention;

Fig. 2 is another vertical cross-sectional view taken transversely to Fig. 1;

Fig. 3 is a vertical cross-sectional view of a slightly modified form of apparatus; and

Fig. 4 is a diagrammatic view of a portion of the apparatus shown in Fig. 3.

Referring for the present more particularly to Figs. 1 and 2, a refrigerating apparatus embodying features of this invention may comprise a water cooling cabinet having a water cooling system mounted therein. The water cooling system is so related to the cabinet that the parts of the water cooling system which are liable to necessitate adjustment or repairs, or which must be assembled within the cabinet, are readily accessible therein. The cabinet and the water cooling system are thus correlated to furnish a very efficient water cooling apparatus.

The cabinet may comprise metal framework having vertical corner angle irons 22 joined at the top by horizontal corner angle irons 23. The bottoms of the angle irons 22 may be joined by horizontal corner angle irons 24. If desired, the horizontal angle irons 24 may be provided with ornamental pedestal members 25. The pedestal members 25 may be provided with horizontal attaching plates 26 through which bolts 27 may pass in order to attach the same to the angle irons 24. The pedestal members 25 may be provided with an upwardly directed extension 28 adapted to form a channel 29 intermediate the extension 28 and the iron 24 for receiving the bottoms of the panels hereinafter to be more fully described to form one specific embodiment of

quickly detachable panel securing means. The angle iron members of the frame may be joined at the corners in any suitable manner and may be reinforced by gussets 30, which may be riveted or spot-welded to the angle irons of the frame.

The frame heretofore described, or any other suitable frame, may have mounted thereon the panel structure of the cabinet. The panel structure may comprise four vertical panels 31 two of which disposed opposite one another are provided with vertical flanges at their vertical edges. The other two opposed panels may be provided with substantially straight edges, although these edges may be slightly offset for receiving the vertical flanges of the first two panels to thereby enhance the appearance and efficiency of the joint thus formed. When assembled, the panels 31 are adapted to interlock at the corners. The lower edges of some or all of the panels are adapted to fit in the channels 29, and, for convenience, the bottoms of the panels may be offset at 35 in order to provide an efficient joint with the channels 29. The panels thus assembled are held from spreading apart at the top by any suitable means such as by means of the top plate 37. The top-plate 37 may be provided with a downwardly directed flange 38, which, in this particular embodiment, is a continuous flange around the entire periphery of the plate 37. The upper portions of the panels may be provided with a slight bend 39 in order to hold the panels more snugly under the flange 38 and thus prevent rattling. The tops of the panels 31 and 32 terminate a slight distance below the top 40 of the flange 38. Thus the panels, when they are to be removed, may be lifted slightly so that their lower edges are lifted above the upwardly directed extension 28. The lower portion of each panel may be then swung outwardly and the entire panel 40 swung slightly downwardly in order to remove its upper edge from under the flange 38. In this particular embodiment, either one of the flanged panels may be first removed without disturbing other panels. Also after removing both of the 45 opposed flanged panels 31, either one of the other two opposed panels may be removed. It is thus apparent that the side panel structure of the cabinet may be assembled without the use of screws, bolts or other fastening devices of that 50 character, and that the panels may be removed almost instantaneously.

If the mechanical refrigerating system includes an air-cooling condenser, or if it is otherwise desirable, louvers 41 may be struck either outwardly or inwardly in the panels for permitting cir-

culation of air into the cabinet. These louvers are also convenient when removing the panels, as they may be used as handles for the purpose. It is obvious that the louvers may be omitted and handles of some other character may be provided if desired.

The top plate 37 may be of any suitable construction, but in this particular embodiment, it is preferred to have a substantially flat portion 50 from which the downwardly directed bowl 51 may be integrally pressed. The flange 38 may be integrally formed by providing the curved portion 40 which also acts as a rim for preventing water from running down the side of the cabinet if it should be splashed on portion 50. The panels 31 and the top 37 may be formed of porcelain enameled sheet metal and thus present a very attractive appearance as well as a very sanitary construction. The bottom of the bowl 51 may be provided with a countersunk opening 52 to which the drain fitting 53 may be attached. The drain fitting 53 is of any suitable construction, and may include a lower flanged structure 54 having threaded engagement with an upper flanged structure 55 adapted to pinch between their edges the periphery of the countersunk opening 52.

Another opening 56 may be provided along the slanting portion of the bowl 51. Through this opening a bubbling cup fitting 57 may be attached to the top 37. The fitting 57 may include a water discharge nozzle having a lip guard provided with an opening, as is conventional in such bubblers, through which the stream from the nozzle is adapted to pass. The lower portion of the guard may also be provided with openings to permit the fitting to drain completely. The upper part of the fitting 57 has a plate or flanged and threaded engagement with a lower portion 62 thereof and these two portions are adapted to engage between them with suitable gaskets, if necessary, the portion of the bowl surrounding the opening 56. The fixture 57 is adapted to be connected by suitable tubing to a combined automatic pressure-regulator and valve 63. The valve is adapted to be moved by a spring returned handle 64. The fitting 63 is also of the flanged and threaded engagement type adapted to engage a portion of the plate 37 in the manner heretofore described for fittings 53 and 57. An automatic pressure-regulator within the fitting 63 limits the pressure on the nozzle of the bubbler. The fitting 63 is connected by means of flexible copper tubing 65 with a water cooling tank (not shown) and located within a casing generally designated as 66. It is also connected by flexible tubing 67 (see Fig. 2) with the fitting 57. Thus it is seen that water delivered from the water cooling tank within casing 66 to the fitting 63 is delivered to the fitting 57 when the valve is operated. The stream leaving the nozzle of the bubbler is directed upwardly in a slanting direction so that it does not fall back on the fitting 57 but falls on some portion of the bowl 51 and forms at its apex the desired stream for permitting a person to drink without touching the fixture 57. The maximum pressure permitted by the automatic pressure-regulator prevents the stream from being directed beyond the periphery of the bowl 51.

The top plate 37 may be moved slightly upwardly when desired merely by unscrewing the top portion 55 of the drain fitting 53. Since the connections between the plate 31 and the tank 66 are flexible, the top plate 37 may be moved

relatively to the tank 66 and to the frame of the cabinet. If desired the drain fitting 53 may be rigidly secured to the frame by means of a U-shaped metal piece 68 to which the lower portion 54 of the drain fitting 53 may be bolted. If desirable, suitable cushioning means 69 may be interposed between the plate 37 and the top angle irons 23. The pipe connections can thus be made between the top 37 and the tank 66 and the top may then be lowered into place.

The water cooling mechanism may be of any suitable construction. For instance and as before stated it may include a substantially cylindrical tank (not shown) within casing 66 and suitably insulated therefrom. An evaporator (not shown) of a closed refrigerating system is mounted within the water cooling tank in any suitable or conventional manner. The water cooling evaporator may be of the character disclosed in the patent to R. G. Osborn, No. 1,556,708, patented October 13, 1925, with the exception that the depending loops may be omitted, if desired. The water cooling evaporator may have an end plate carrying a float valve-controlled valve and outlet fitting substantially of the type disclosed in the patent to Osborn. The water from any suitable supply enters the water cooling tank through the inlet 85 and leaves the tank through the outlet 86 (see Fig. 1). Either the inlet 85 or the outlet 86 may be positioned at a point where the water is last to freeze should the water in the cooling tank be accidentally frozen. This is in accordance with the disclosure in the Patent No. 1,847,092 hereinbefore referred to. The casing 66 containing the water cooling tank together with the insulation therebetween may be suspended from the upper angle iron 23 by means of straps 87 passing underneath the cylindrical casing 66.

A pan 88 may be suspended from the casing 66 in order to catch any condensation which may form on this casing. However, under some circumstances the heat generated by the compressor, hereinafter to be described, may be sufficient to prevent the formation of enough condensation to cause the same to drip in the pan 88. If any water flows into the pan 88 it is evaporated by the heat from the compressor or by the air flowing through the cabinet.

The liquid cooling evaporator may be of the volatile or unvolatile refrigerant type. In this particular embodiment, it may be a float valve-controlled evaporator of the type disclosed in the patent to Osborn. The evaporator 76 may be supplied with liquid refrigerant from any suitable source. For instance, it may be supplied with liquid refrigerant by a refrigerant liquefying unit which may be located within the cabinet 20, if desired. The refrigerant liquefying unit may comprise a compressor 91 delivering compressed refrigerant to a condenser 92 which delivers liquefied refrigerant to a receiver 93. The liquid refrigerant in the receiver 93 may be delivered by the pipe 78 to the evaporator. The refrigerant evaporated in the evaporator may be returned by the pipe 79 to the compressor 91, preferably in the crankcase of the compressor. The compressor 91 may be driven by a motor 94 which may be connected by the belt 95 with the compressor 91. The motor 94 may be started and stopped by means of a snap switch 96 operated by an expansible bellows 97 which may be connected with the evaporated refrigerant line 79 by means of the pipe 98. The motor 94 may be provided with a fan

99 which is adapted to cause circulation of air for the cooling of the condenser 92, the compressor 91 and the motor 94. The refrigerant liquefying unit 90 may be mounted on a substantially box-like angle iron frame 100 which may be provided with pedestals 101 adapted to rest on rubber mountings 102 and which may be laterally spaced from the frame by means of rubber cushions 103.

The water cooling apparatus may be slightly modified. For instance it may be of the type disclosed in Figs. 3 and 4 in which there are two water outlets 110 and 111. The water outlet 110 may be of the bubbling cup type and may be controlled by the combined valve and pressure regulator 112. The fittings 112 and 111 may have a water regulator which maintains a substantially constant pressure on either of the fittings 110 and 111 and thus limits the pressure of the stream leaving these fittings. The fitting 111 may be of the type ordinarily used to fill tumblers. In this particular embodiment, the top plate 31a has the two bowls 51a and 51b. These two bowls are symmetrical with respect to each other. Thus either the type of fitting 111 or the type of fittings 110 and 112 may be installed in either of the bowls 51a or 51b. The opening 116 may be plugged when type of fitting 111 is used or it may be used for the fitting 110 while at the same time the opening 117 would be used for a valve fitting such as 112. It is thus seen that these fittings are interchangeable in either of the bowls 51a or 51b. The panel structure for the water cooling apparatus disclosed in Figs. 3 and 4 is substantially the same as that heretofore disclosed with the exception that the top plate 31a is made for a double water outlet. The drain fittings 53a are connected by means of U-shaped angle irons 68a to the upper angle iron members 23a. The tank 70a is connected by means of flexible tubing 65a and 65b with the fittings 111 and 112 in order that the plate 31a may be moved upwardly merely by the removal of the drain plates 55a.

In this embodiment the compressor 120 delivers compressed refrigerant to a water cooled condenser 121. The condenser 121 delivers liquefied refrigerant through the pipe 122 to the evaporator 123. The evaporated refrigerant returns by the pipe 124 to the compressor 120. The compressor 120 is driven by means of a motor 125 controlled by a snap switch 126. The snap switch 126 is operated by an expandible bellows 127 connected by a pipe 128 with the evaporated refrigerant line 124. Water from any suitable supply is delivered by a pipe 130 to the condenser control switch 131 which is operated by an expandible bellows 132 which is connected to the refrigerant pressure line 133. Thus water is delivered through the pipe 134 to the condenser 121 whenever required by the portion of the condenser 120. Another branch 135 from the pipe 130 delivers water to the tank 70a where it is cooled by the evaporator 123. The cooled water is delivered by the pipe 136 to the fittings 110 and 111. The valve 112 controls the flow of water to the fitting 110. Waste lines 106a lead from the bowls 51a and 51b. These are connected to the drain pipe 140 which also receives the discharge from the condenser 121 by means of a pipe 141 connected to the water jacket of the condenser 121. The structure of the modification shown in Figs. 3 and 4 is more particularly described, in some respects, in the Patent No. 1,847,092 hereinbefore referred

to. The lower pedestal structure 150 may differ slightly from the pedestals 25. In this particular embodiment, the pedestal structure 150 may be a solid metal square structure which is adapted to be connected to the vertical angle iron members 22a similarly to the pedestal structure member 25. The outer casing 72a may be supported by longitudinal angle iron members 151 connected to the angle iron members 22a.

10 Access is provided to the evaporator 123 by the removal of the panel 32a and by the removal of the insulation 152 at the end of the casing 72a.

15 The evaporator 123 may be of the type more fully described in the patent to Jesse G. King, No. 1,929,697. The fins 123a in the evaporator may be made of a shape to render the evaporator readily insertable in and removable from the tank 70a. For instance, the fins 123a may be 20 circular, having approximately the same diameter as the cylindrical float chamber to which the numeral 123 has been applied in Fig. 3. Thus the evaporator may be readily inserted through a circular opening in end wall of the tank 70a. The opening may be closed by a flanged construction on the float chamber.

25 The heat from the compressor in water coolers embodying this invention also aids in preventing condensation on the waste water bowls. By 30 making the bowls integral with the top and countersunk therein, the heat from the machinery prevents condensation on the bowls.

While the form of embodiment of the invention as herein disclosed, constitutes a preferred 35 form, it is to be understood that other forms might be adopted, all coming within the scope of the claims which follow.

What is claimed is as follows:

1. In a water cooler having an inner frame and 40 outer panel members covering said frame, a sheet metal top member having a well portion, a flat portion surrounding said well and an embossed portion surrounding said flat portion and terminating in a skirt overlying said panel members and spaced therefrom on all sides of said cooler 45 so as to prevent water from running down the sides of said panel members, each of said portions being formed integral with said top member, said well portion extending below the general plane including said other portions and provided with a water bubbler and a drain plate attached to a stationary drain pipe carried by said frame, the underside of said flat portion overlying said inner frame and being directly supported thereby on all sides of said cooler, said drain plate and drain pipe forming the sole means for securing 50 said top member to said supporting frame thereby producing a stable but quickly removable cooler top assembly.

2. In a water cooler having an inner frame and outer panel members covering said frame, a sheet metal top member having a well portion, a flat portion surrounding said well and an embossed portion surrounding said flat portion and terminating in a skirt overlying said panel members and spaced therefrom on all sides of said cooler 55 so as to prevent water from running down the sides of said panel members, each of said portions being formed integral with said top member, said well portion extending below the general plane including said other portions and provided with a water bubbler and a drain plate attached to a stationary drain pipe carried by said frame, the underside of said flat portion overlying said inner 60 frame and being directly supported thereby on at

least two opposite sides of said cooler, said drain plate and drain pipe forming the sole means for securing said top member to said supporting frame thereby producing a stable but quickly removable cooler top assembly.

3. In a water cooler having a body provided with a generally vertical outer casing, a sheet metal top member having a well portion, a main body portion surrounding said well portion and a skirt overlying said vertical outer casing, each of said portions being formed integral with said top member, said well portion extending below the general plane including said other portions and provided on top with a water bubbler, a valve and a drain plate attached to a stationary drain pipe carried by said frame; a flexible water pipe extending from said body to said valve, a water flow connection between said valve and bubbler, said drain plate and drain pipe forming the sole

means for securing said top member over said vertical outer casing thereby producing a stable but quickly removable cooler top assembly.

4. In a water cooler, an outer vertical casing enclosing the main portion of said cooler, an integral metal top provided with a well portion and a skirt overlying the sides of said casing, said top provided on its upper side with a bubbler, and a drain opening, a valve secured to said top with a control handle extending from its upper part, a flexible water pipe extending from said main portion to said valve, a water connection between said valve and bubbler, a stationary drain pipe in said main portion, and means extending through said drain opening for securing said top over said casing.

JOHN A. MACREADY.
